UNITED STATES PATENT OFFICE.

JOHN CANELLES, OF DULUTH, MINNESOTA.

SUPPLEMENTAL LOCK AND KEY DEVICE.

Application filed April 27, 1923. Serial No. 635,056.

To all whom it may concern:

Be it known that I, JOHN CANELLES, a citizen of the United States, residing at Duluth, in the county of St. Louis and State 5 of Minnesota, have invented certain new and useful Improvements in Supplemental Lock and Key Devices, of which the following is a specification.

This invention relates to improvements in 10 lock mechanisms.

The primary object of this invention is the provision of a supplementary lock and key mechanism, which may be used in connection with ordinary types of "warded" or 15 "lever-tumbler" locks to make the same more secure, so that the same may not readily be picked.

A further object of this invention is the provision of a novel type of lock mechanism 20 which may be used for operating ordinary types of locks, such as "warded" or "lever-tumbler" locks, embodying a key portion adapted to operate the bolt mechanism of the ordinary lock, and including a "pin-tumbler" type of lock connected to the key 25 for operation thereof.

A further object of this invention is the provision of a lock device which may be installed supplementary to an already positioned locking mechanism, embodying means 30 for attaching the same in operable manner to the key of the already positioned locking mechanism, and itself adapted for operation by a second key.

Other objects and advantages of this invention will be apparent during the course 35 of the following detailed description.

In the accompanying drawing, forming a part of this specification, and wherein 40 similar reference characters designate corresponding parts throughout the several views,

Figure 1 is a cross sectional view, taken through a support, showing in section the 45 improved supplementary lock and key as used in connection with a conventional type of lock, the parts being shown in position for the turning of the key in the conventional lock to operate the bolt of the same.

Figure 2 is a cross sectional view, showing 50 elements similar to those illustrated in Figure 1, however, showing the supplementary lock tumblers in position to prevent operation thereof.

Figure 3 is a front elevation of the im- 55

proved supplementary lock and key device, showing the same exteriorly attached to a support.

Figure 4 is a bottom plan view of the im- 60 proved supplementary locking device.

Figure 5 is a cross sectional view, taken substantially on the line 5—5 of Figure 4.

Figure 6 is a cross sectional view, taken substantially on the line 6—6 of Figure 2.

In the drawing, wherein for the purpose 65 of illustration is shown but the preferred embodiment of this invention, the letter A generally designates the improved supplementary lock and key, which is adapted for mounting upon an ordinary support B, 70 such as a door or casing; for the control of a conventional type of lock C, which may be of the "warded" or "lever-tumbler" type. The improved supplementary lock and key device A preferably includes the key portion 75 D for direct operation upon the bolt of the conventional lock C; the locking mechanism E of the "pin-tumbler" type for control of the key D; and a second key F for operation of the locking mechanism E. 80

The support B, may be a door or casing, on the interior surface 10^a of which the lock C is attached. The lock may include the ordinary casing 10 and bolt mechanism 11 85 therein of any of the approved types, adapted to be operated by means of the wing bit 15 of the key portion D.

Referring to the key D, which is adapted for operation of the lock C, the same preferably includes the solid cylindrical shank 90 portion 17, upon the forward end of which the wing bit 15 is formed, as in conventional manner. This key for cooperation with the supplementary lock device may be the ordinary key provided for the lock C, with the shank 17 thereof altered to provide an annular flange 19 adjacent the wing bit 15, and an annular flange 20 in spaced relation with the flange 19 at the rear end of the shank 17. Outwardly of the annular flange 20, a substantially rectangular reduced shank portion 21 is provided, for cooperation with the combination lock, as will be subsequently described. The forward end of the annular shoulder or flange 19 may be tapered in converging relation toward the bit end of the shank 17 to facilitate attachment of the device A with respect to the lock C. 105

Referring to the locking mechanism E, the same preferably includes the case 25, 110

providing a cylindrical shaped chamber 27 way 55 therethrough, within which a revoluble plug 28 is positioned. To reduce the size or exterior dimension of the case 25, a radially 5 extending flange or portion 30 is provided longitudinally thereof, which provides tumbler chambers or recesses 31, communicating with the passageway 27, and adapted for alignment in certain relative positions 10 with the tumbler passageways provided transversely through the revoluble plug 28, as is usual in locks of this construction. The tumbler and complementary driver pins 33 are provided, for the transverse passageways of the case and plug portions 25 and 28 respectively, normally urged by the spiral springs 35 into the longitudinal key way 36 provided through the revoluble plug 28, as in a conventional lock construction of the 15 20 "pin-tumbler" type.

To rotatably secure the plug 28 within the case chamber 27, an annular groove 37 is preferably provided at the forward end of the plug 28, into which a pin 38 secured to 25 the casing 25 extends, to prevent longitudinal detachment of the plug from the case of the lock mechanism E.

Referring to the key D upon the locking mechanism E, the case 25 of the latter is 30 preferably provided with a forwardly extending finger 40, contiguous with the depending flange or portion 30 of said lock case, which extends forwardly of the forward surface of the plug 28. A clamping 35 band 45 is preferably provided, including the bight portion 46, which rotatably receives a portion of the key shank 17 therein, intermediate the spaced annular flanges 19 and 20 of the latter. In this position, the 40 reduced end 21 of the key D is inserted into the forward end of the key way 36 of the lock plug 28, so that there can be no relative rotation of said plug and key D. A spacing sleeve 48 is preferably provided, 45 intermediate the forward end of the clamping band 45, and the forward annular flange 19, which is just sufficient to abut the facing annular margins of the flange 19 and the clamping band bight portion 46. The clamp 50 band 45 preferably provides the depending parallel flanges 50 and 51, which overlie upon opposite sides the forward finger portion 40 of the case 25, and are secured thereto as by means of a rivet 53. In this manner, it is obvious that the key part D is secured to the movable or rotatable tumbler 28 of the lock E, to prevent any relative movement of said parts. It is thus obvious that when the key F for the "pin-tumbler" 55 lock mechanism E is inserted in the key way 36, rotation of the plug 38 will likewise impart rotation to the key D.

To accommodate the supplemental lock and key device A, the support B, is preferably provided with an enlarged passage-

way of the lock C from the outside of the support B. The device A is then inserted into the passageway 55, with the bit 15 of the key D in place within the lock C for the operation of the bolt thereof. An attaching or retaining plate 57 is then detachably secured exteriorly upon the support B, which mounts the lock D in place within the passageway 55, substantially as is illustrated in the drawing. This is a permanent location for the supplemental lock and key device A, and it is to be noted that the key D for the lock C is not to be withdrawn and cannot be withdrawn under any circumstances, except by complete detachment of the device A from the support B. The operation of the key D is only effected by operation of the plug 28, by means of the key F, of a type provided for the pin tumbler type of lock, such as E.

From the foregoing description of this invention, it is apparent that the device herein described, is of a practical nature, in that the same can be conveniently applied to operate common types of lock mechanisms already in place, with but very little alteration to the structure upon which they are placed. The lock in place is thus not only reinforced, but the conventional key for direct association therewith is in such permanent relation thereto that the same cannot be removed by picking.

Various changes in the shape, size, and arrangement of parts may be made to the form of invention herein shown and described, without departing from the spirit of the invention or scope of the claims.

I claim:

1. A device of the class described comprising a key, a lock including a case and a revoluble plug with a keyway therethrough, and means rotatably connecting the key to said case, so that an end thereof extends into the keyway of said plug for rotation therewith.

2. A supplemental lock and key device comprising a key portion, a lock including a case and a revoluble plug having a keyway therethrough, and means for connecting an end of the key in the forward end of the plug keyway, so that rotation of the plug will impart rotation to the key.

3. In a device of the class described, the combination of a key including a bit and an attaching shank, a lock device including a case, revoluble plug, and tumbler means, and a clamp for rotatably receiving said shank of the key and for attachment to said case for rigidly affixing said key to said plug for rotation therewith.

4. A supplemental lock and key device comprising a key providing a shank portion having a pair of annular flanges thereon intermediate the ends thereof, a lock in-

cluding a case portion and a rotatable plug attached to the key way therein, and clamping means connected to said case and rotatably receiving the key shank therein intermediate said annular flanges with an end of said shank in the plug keyway to prevent longitudinal movement of the key with respect to the lock.

5. A device of the class described comprising a lock including a case, a rotatable plug therein, tumbler means for the case and plug, said case having a finger extend-

ing outwardly therefrom forwardly of the front of said plug, a key including a shank, means connecting an end of said shank to said plug to obtain rotation of the key by rotation of the plug, and a clamping band rotatably receiving said shank therein outwardly of said plug and attached to the forwardly extending finger of said case to prevent lateral movement of the key shank with respect to said lock.

JOHN CANELLES.
